CLAIM

The ornamental design for a body for hanging light fixture, as shown and described.

DESCRIPTION

FIG. 1 is a side view of a first embodiment of a body for hanging light fixture;

FIG. 2 is a top view of the body of FIG. 1;

FIG. 3 is a bottom view of the body of FIG. 1;

FIG. 4 is a side view of a second embodiment of a body for a hanging lighting fixture;

FIG. 5 is a top view of the body of FIG. 4;

FIG. 6 is a bottom view of the body of FIG. 4;

FIG. 7 is a side view of a third embodiment of a body for a hanging lighting fixture;

FIG. 8 is a top view of the body of FIG. 7; and,

FIG. 9 is a bottom view of the body of FIG. 7.

The broken lines showing the finials are for illustrative purposes only and form no part of the claimed design.
